UNITED STATES PATENT OFFICE.

JOSEPH T. CRAW, OF JERSEY CITY, NEW JERSEY.

SMOKING TOY.

SPECIFICATION forming part of Letters Patent No. 484,180, dated October 11, 1892.

Application filed December 11, 1891. Serial No. 414,723. (No model.)

To all whom it may concern:

Be it known that I, JOSEPH T. CRAW, of Jersey City, in the county of Hudson and State of New Jersey, have invented a new 5 and Improved Smoking Toy, of which the following is a full, clear, and exact description.

The invention consists in a simple and novel suction device for smoking a cigarette, and also includes in the preferred form the 10 representation of a head having eyes arranged to be rocked and rotated by the vibrations incident to the operation or manipulation of the suction device.

Reference is to be had to the accompanying 15 drawings, forming a part of this specification, in which similar letters of reference indicate corresponding parts in all the figures.

Figure 1 is a perspective view of a toy embodying my invention. Fig. 2 is a vertical 20 section on line 2 2, Fig. 3. Fig. 3 is a rear elevation, and Fig. 4 is a broken perspective view showing the manner of operating the suction device.

In constructing a toy in accordance with my 25 invention a box-like structure A is provided, preferably rectangular in shape and formed of pasteboard or like material of a nature to permit the structure to be partially collapsed to expel air therefrom, and which, further,

30 will resume its normal shape and size when the collapsing-pressure is relieved, and thus cause a suction. In the front of the box A an aperture a is produced for receiving the end of a cigarette, as B, snugly therein, the

35 box being otherwise practically air-tight. The back a' of the box is scored in curved lines near each side edge, as at a², and as a result when pressure is applied at the side edges or angles a³ and the box partially col-

40 lapsed, as shown in Fig. 4, the back a', between the scores a², will be flexed outward, and when the pressure is relieved the said back, by reason of the said scores, will spring inward and the box will resume its normal

45 shape, this alternate collapsing and resumption of its normal shape serving to create an alternate suction and expulsion of air and smoke through the cigarette. The box A is secured by its front a⁴ to the back of a disk

50 or sheet C or its equivalent, near the bottom of the same, the disk being also preferably of cardboard, and it is fashioned to simulate a

human head, nondescript, or caricature. The mouth c is produced at the aperture a, and the upper lip c' is made to be flexed outward 55 and to bear with a slight pressure against the cigarette B to better hold the latter. The nose c² is also made to flex outward, and over the same is passed a cord or thread D, the ends of the cord passing at the rear of the 6c disk C and diagonally across the eye-aper- tures c³ through balls E, the latter having a through-bore for the loose passage of the cord.

The balls are painted at two opposite sides 65 to simulate eyes. With this construction the eyeballs will respond readily to the vibratory movement given the structure in manipulat- 70 ing the suction device A, and as the eyeballs are rocked and rotated on their cords the ex- pression of the face will be rapidly changed, the eyes thus moving and changing in conso- 75 nance with the smoking action caused by the suction device. The eyes will also move when the structure is bodily shaken; but the 80 desire is to form a structure which when rest- ing on a suitable support and its suction de- vice operated will be so vibrated as to move the eyes, the movement of the eyes and the ejection of the smoke thus being in conso- 85 nance.

The device is of cheap and simple construc- 90 tion, efficient for its purpose, and the action of the suction device is not so strong as to rapidly consume the cigarette. 85

Having thus fully described my invention, I claim as new and desire to secure by Letters Patent—

1. The combination, in a smoking toy, of a suction device, a disk held thereto and ex- 90 tends above the same, the disk simulating a head, and eyes held loosely to the head and having a rocking movement when the ma- nipulation of the suction device vibrates the disk, substantially as described. 95

2. The combination, in a smoking toy, of a suction device scored in curved lines, as de- 100 scribed, a disk held in fixed relation thereto and simulating a head, the suction device having an aperture leading to the mouth of the head, adapted to receive a cigarette, and eyes loosely held in place to rock in response to the vibrations caused by manipulating the suction device, substantially as described.

3. The combination, in a smoking toy, of a disk secured thereto and made to simulate a head, eyes held in diagonal positions in the head by a cord, and a suction device held to the disk and having an aperture for receiving a cigarette, the manipulation of the said suction device serving to vibrate the structure and rock the eyes, substantially as described.

4. The herein-described suction device, consisting of a box-like structure of stiff material scored in curved lines adjacent to certain of its angles, substantially as specified.

JOSEPH T. CRAW.
